THOMAS L. HOLLINGSWORTH, OF ELYRIA, OHIO, ASSIGNOR TO THE FAY RUBBER PRODUCTS COMPANY, OF ELYRIA, OHIO, A CORPORATION OF OHIO.

HEEL-RETAINING DEVICE.

1,359,805.

Specification of Letters Patent. Patented Nov. 23, 1920.

Application filed May 31, 1918, Serial No. 237,381. Renewed March 13, 1920. Serial No. 365,660.

To all whom it may concern:

Be it known that I, THOMAS L. HOLLINGSWORTH, a citizen of the United States, residing at Elyria, in the county of Lorain and State of Ohio, have invented a certain new and useful Improvement in Heel-Retaining Devices, of which the following is a full, clear, and exact description, reference being had to the accompanying drawings.

This invention relates to devices for retaining the lower section or lift of a heel for a shoe, and is particularly adapted for use with resilient heels. An object of the invention is to provide a simple, effective retaining device which may be very conveniently applied and may hold a heel section very securely and still permit comparatively easy removal when it is desired to replace the worn resilient portion or section of the heel. A more specific object of the invention is to avoid the difficulties and inconveniences incident to securing resilient heel sections by the use of nails or pegs. Other objects will become apparent in the following description which refers to the drawings; the essential characteristics are summarized in the claims.

In the drawings, Figure 1 is a vertical longitudinal section through the heel illustrating my securing device; Fig. 2 is a bottom view of the heel; Fig. 3 is a bottom plan of the more solid portion of the heel to which the resilient section is secured showing the receiving plate coöperating with the securing elements of the resilient section; Fig. 4 is a sectional detail on the same plane as Fig. 1, illustrating the manner in which the securing devices coact; Fig. 5 is a sectional detail taken on the line 5—5 of Fig. 1; Fig. 6 is a detail in plan of the securing member for the removable section before being embedded in the heel.

Describing the parts by the use of reference characters, the upper of a shoe is indicated at A and the sole at B, in broken lines, while C indicates the usual solid portion of the heel made of leather or like material.

Secured to the bottom surface of the heel C is a plate 10 having its perimeter substantially the shape of the heel and preferably somewhat smaller. It is shown as being set in so that its bottom surface is flush with the surrounding surface of the lower layer of the heel portion C, thus presenting a flat

surface to the removable section to be fitted thereon. The plate 10 may be secured to the heel C in any suitable manner, for example, I have shown pegs or nails 11 and 12, the heads of which are fitted in chamfered openings in the plate. 60

The plate 10 is provided with gripping jaws, formed as follows: Slits 15 are cut at separated points in the plate, preferably parallel and at the ends of these slits the metal is cut transversely thereof for a short distance as indicated at 16, and the metal of the plate at each side of the cut 15 is turned upwardly sharply to present gripping jaws 18. As these portions 18 are 65 turned upwardly, it will be noted (from Fig. 4) that they present two comparatively sharp separated edges at each side of the opening between them.

At D is indicated a rubber heel or heel section comprising the lower lift of the heel and embedded in the resilient sections is a plate 20. This plate 20 is provided with laterally extending projections 22 formed by cutting away the metal around three sides 80 of an opening 23 and turning the metal thus freed upwardly at substantially right angles to the plane of the plate. The openings 23 are preferably so cut that the metal turned upwardly therefrom is tapered on its opposite upright edges and is normally horizontal on its upper edge. This plate may be embedded in the rubber of the resilient section, by any suitable process, in substantially the position indicated and when so 85 embedded may serve to secure the resilient section to the section C, it being only necessary to present the projections 22 to the notches formed by the inwardly turned jaws 18 and forcibly move the heel D to the heel 90 C, thus thrusting the projections 22 between the jaws until the lower and upper surfaces of the heel sections C and D, respectively, meet as shown in Figs. 1 and 4.

The material of the section C is preferably 100 cut away forming openings 25, occupied by the projections 22, although these projections may, if desired, be sharpened and forcibly driven into the material of the heel C. In the latter case, the application of the 105 first rubber heel to the leather section forms openings which may be occupied by the projections 22 of new heels used to replace worn heels. As the projections 22 are forced inwardly between the jaws 18, these jaws are 110

separated materially and tend to spring inwardly toward each other, thus causing the sharp edges thereof to firmly grip the projections 22 and it will be noted that these edges are so presented to the projections that inward and upward movement may be more easily accomplished than the downward movement, as the downward movement tends to strengthen the jaws 18 drawing them still more tightly into engagement with the projections.

The heel D is shown as having a recess E, formed in its lower side, leaving a broad rim around the perimeter of the heel section 15 which provides the desired treading surface and also has the following advantage. It will be noted that the recess leaves but a thin layer of rubber beneath the plate 20, whereby blows may be given directly opposite the projections 22 and the heel may be more effectively put into place than were the blows struck upon the rubber of materially greater thickness, between the plate and the bottom of the heel. The principal 25 advantage, however, is that the tread portion is comparatively narrow, which adds to the resilience of the heel and consequently adds to its wear.

To remove the heel, it is only necessary to 30 thrust a wedge-shaped instrument between the sections D and C and inwardly toward the projections 22 and forcibly draw these projections outwardly from engagement with the jaws 18 whereupon an entirely new 35 heel may be placed upon the heel C before that section is worn. The placing of the heel in position is so simple in operation that it does not require the services of a cobbler, and the wearer of the heels equipped with 40 my improved securing device may merely remove them with any pointed instrument, such as a screw driver, and replace them with new ones in a few moments. Experience through extended tests have proven that 45 this securing device is very effective.

Having thus described my invention what I claim is:

1. In a securing device for lower heel sections, the combination of a plate secured to 50 the upper section of the heel, and having an opening formed in said plate, the metal surrounding said opening being turned upwardly and inwardly and being constructed and arranged to yieldingly engage a pro-

jection extending into said opening and 55 serving to secure the removable section.

2. A device for securing a removable heel section, comprising a plate secured to the solid portion of the heel and having an opening, the material at the sides of said opening 60 being turned upwardly and presenting a sharp edge, and a projection extending into said opening from the removable heel section, and tending to separate the edges at the sides of the opening causing the edges 65 to bite into and retain the projection.

3. In a device of the character described, the combination of a solid heel section and a removable lower section, a securing device 70 for the lower section comprising a metal plate carried by the upper section and having a slot, the metal at each side of the slot being turned from the plane of the plate and presenting sharp edges toward the slot, a plate secured to the removable section and 75 a projection extending from the last named plate into said slot and firmly engaged by the metal at each side of the slot.

4. In a device for securing lower heel sections, the combination of a plate secured to 80 the solid portion of the heel of the shoe, said plate having a plurality of slots, the metal at each side of the slot being turned upwardly, a removable section having a 85 plate embedded therein, and projections extending from said plate through said slots, the metal at each side of the slot tending to bite into the plate.

5. In a device for retaining a resilient heel, the combination of a plate secured to 90 the solid portion of the heel and having gripping members formed by cutting a slit in the heel and turning the metal at each side of the slit inwardly and upwardly, a resilient heel section, and a plate embedded 95 in the resilient heel section having upward projections rigid therewith and adapted to be forced into said grippers, tending to separate the same, whereby the grippers firmly engage such projections said grippers being so shaped that they resist downward movement more effectually than upward movement of the projections.

In testimony whereof I hereunto affix my signature.

THOMAS L. HOLLINGSWORTH.
